BUTTON

Richard Metzger, New York, N. Y., assignor to
 Leo H. Hirsch & Co., New York, N. Y., a partnership composed of Leo H. Hirsch and Lionel Goldfrank

Application May 26, 1939, Serial No. 275,783

2 Claims. (Cl. 24—90)

This invention relates to a button of the type having a shank by means of which it may be attached to a garment or other article, and more particularly to a button in which a wire shank is attached to a head or disk of pearl or like material.

5 Imperforate pearl buttons are extensively used on uniforms and other articles of apparel both for utilitarian and ornamental purposes. The 10 metal shanks heretofore used on buttons of this type have been of relatively expensive construction. The heads of the buttons are generally made of disks of natural pearl shell, either fresh water or ocean. Because of the frangible, laminar, 15 irresilient character of pearl, considerable difficulty has been experienced in securely fastening the shank to the head.

The primary object of this invention is to provide a pearl button having a shank of simple 20 and inexpensive construction which is securely attached to the head in such manner as to withstand disconnection by direct pull or by twisting movement.

The shank is made of wire formed in U-shape 25 and attached to the button-head at two separated points. I have found in practice that the shank and head of a button constructed according to my invention are secured together so firmly that it is impossible to disconnect the shank 30 either by direct pull or by a twisting movement without breaking or damaging the pearl head.

The present invention is especially directed to the construction on a high production basis of pearl buttons or the like. By reason of the brittle 35 nature of the material, it is impossible to undercut it at a steep or wide angle as such drilling would weaken and break the material. It is also difficult to cut or ream the pearl for the reception of a shank having screw threads or the like 40 on its exterior surface. Where bell shanks have been used, it has been necessary to undercut the pearl and to tap the shank in by hand, resulting in a low rate of production.

The above and other objects and advantages 45 of my invention will become apparent as the description proceeds, reference being had to the accompanying drawings, in which:

Figure 1 is a perspective view of a button embodying the invention;

50 Fig. 2 is an exploded view of the button head and shank, prior to assembly, the head being shown in section; and

Fig. 3 is a similar sectional view showing the button and shank after assembly.

55 The button comprises a head 10 made of a disk of shell pearl, either fresh water or ocean, having two holes 11 and 12 drilled therein, which holes are relatively widely spaced to provide sufficient material between them for strength. These holes 60 are not drilled all the way through the disk and

are arranged at a slight angle to each other as shown in Fig. 2, the angle being only a few degrees off perpendicular. The two holes in the button disk may be drilled in a single operation on a multiple hole drilling machine. The holes are of slightly smaller diameter than that of the wire of the shank 13 so that the legs of the shank will fit tightly in the holes. I have found that a difference in diameter of .0025 of an inch is sufficient.

10 The shank 13 is preferably made of a semi-hard tempered wire and is bent in substantially U-shape having two legs 14 and 15 which are arranged either in parallel or in slightly diverging relation. The lower ends of the legs 14 and 15 are spaced apart the same distance as the entrances to the holes 11 and 12 in the disk so that they will be in aligned relation when being assembled.

15 The shank members 13 may be simply and inexpensively cut and formed by means of suitable dies in a single operation from a continuous spool of wire. The forming dies may also serve to 20 guide the shanks in proper relation to the holes in the head during assembly of the parts.

25 Upon assembly, it will be noted that the legs 14 and 15 will be forced into the divergently inclined holes 11 and 12 and that their lower ends will be directed slightly out of line with the axis of the legs. The shank is thereby held to the 30 head 10 not only by frictional engagement but also by the slight spread of the lower ends of the legs.

35 From the foregoing description it will be seen that the invention provides a simple and inexpensive construction for easily attaching and durably securing the shank to the button head or disk. While the invention is particularly adapted to the manufacture of shell pearl buttons, it may be employed in the construction of buttons 40 of other similar material.

What I claim is:

1. A pearl button comprising a head having two spaced apart apertures extending part way therethrough at a slightly divergent angle to each other, and a substantially U-shaped wire shank having two legs the lower end portions of which are secured with a driving fit in said diverging apertures and extend slightly out of line with the longitudinal axes of the legs.

50 2. A pearl button comprising a disk-like head having two spaced apart apertures extending from one surface part way through the head at a slightly divergent angle to each other, and a U-shaped wire shank having two substantially 55 parallel legs the lower end portions of which are secured with a driving fit in said diverging apertures and extend slightly out of line with the longitudinal axes of the legs.

RICHARD METZGER. 60
